UNITED STATES PATENT OFFICE.

CHARLES E. F. AHLM, OF CLEVELAND HEIGHTS, AND HARRY Y. HALL, OF CLEVELAND, OHIO.

BRUSH-HOLDER FOR DYNAMO-ELECTRIC MACHINES.

1,287,812.

Specification of Letters Patent. Patented Dec. 17, 1918.

Application filed April 17, 1918. Serial No. 229,086.

To all whom it may concern:

Be it known that we, CHARLES E. F. AHLM and HARRY Y. HALL, citizens of the United States, residing at Cleveland Heights and Cleveland, respectively, in the county of Cuyahoga and State of Ohio, have invented a certain new and useful Improvement in Brush-Holders for Dynamo-Electric Machines, of which the following is a full, clear, and exact description, reference being had to the accompanying drawings.

This invention relates to mechanism for holding the brushes in dynamo electric machines and giving them proper pressure on a commutator or collector. One of the objects of the invention is to provide such a device in a simple and effective form, which may be easily disconnected, removed and replaced, thus allowing the ready substitution of new brushes. Another object is to enable the spring force to be accurately adjusted so that the brushes may seat with the desired pressure. Our brush holder is illustrated in the drawings hereof and is hereinafter more fully explained and its essential novel characteristics are set out in the claims.

In the drawings, Figure 1 is a side elevation, partly broken away, and in section, of a dynamo equipped with my brush holders; Fig. 2 is an end view of such dynamo; Fig. 3 is an end elevation from the interior of the dynamo looking toward the brushes, the position of the commutator being indicated by a circle; Fig. 4 is a cross section through a portion of the motor casing and through the supporting part of one of the brush holders; Fig. 5 is a partial plan of one of the brush holders; Fig. 6 is a sectional elevation of a brush holder and parts of the supporting frame and the commutator, illustrating a somewhat different system of electrical connection to the brushes; Fig. 7 is a sectional elevation of a portion of a brush holder wherein the stud is secured to the head by bakelite; Fig. 8 is a fragmentary view of bus-bars which may be employed.

In Figs. 1 and 2, 10 indicates the dynamo casing, 11 the shaft of the armature or rotor, and 12 a suitable commutator. 13 indicates a dish-shaped member secured to the end of the motor frame and having an opening 14 surrounding the armature shaft. This dish-shaped frame member 13 carries our

holders for brushes acting on the commutator 12, as hereinafter explained.

20 indicates spider-like plates or disks adapted to be secured by screws 21 over openings 15 in the frame member 13, each disk forming the support of one of the brush holders. These disks 20 may be dished, as shown in Fig. 1, if desired.

To carry the brushes, each disk 20 insulatingly supports a stud 22. This stud is shown as provided with a collar 23 and it passes through a pair of insulating washers 24 and 25 which seat in an opening in the disk 20. On the outer side of the insulating washer 25 is a plate 26, and bearing against this are nuts 27 and 28 screwing onto the threaded outer portion 29 of the stud.

The brushes are designated 30. They are mounted on the ends of arms 31 which loosely surround the stud 22. Each arm is provided with a tubular hub 32 giving it a good bearing on the stud. The brush is secured to the arm in any suitable manner. As shown, the side of it bears against a flat face 34 while the end of the brush engages an overhanging flange 35, and the brush is secured by a screw 36. As many arms may be employed on the stud as desired. We have shown two arms 31 carrying two independent brushes.

To give the brush the desired spring pressure against the commutator or collector, we provide the coiled spring 40 which makes several turns in a helical form about the hub 32 and has one end anchored to the stud 22 and the other to the arm 31. As shown, the movable end of the spring is bent at right angles and passes through an opening in the arm, as indicated at 41 in Fig. 5. The stationary end of the spring passes through an opening in the stud 22.

To properly position the brush arms on the stud, I locate them by suitable collars as 44 and 45. These collars surround the stud and are shown as secured thereto by the inner ends 43 of the springs 40 which thus act also as cotter pins. Where two brushes are employed, as shown, the first brush is held with reasonable closeness between the collar 23 and the collar 44, and the second between the two collars 44 and 45, and so on for more brush arms.

It will be seen that the holder described

55

70

75

105

makes a simple self-contained device which may be readily removed from the motor frame whenever desired, by taking out the screws 21 which hold the disk heads 20 to the frame member 13.

The holding screws 21 for the heads of the brush holders are arranged equidistantly about the axis so that the screw holes are interchangeable among the different screw holes in the frame members. Accordingly, the spring pressure on the brushes may be increased or diminished by turning the head 20 to give the proper pressure and inserting the screws in the corresponding registering holes.

When the brush holder is put in place there is at first no tension on the springs and then the head is simply turned to give the desired pressure and fastened in place. It will be seen that the screw holes are substantially the same radial distance from the axis of the brush holder as the acting face of the brush, so that substantially the exact pressure of the brush on the commutator or collector may be measured by securing a spring balance to one of the openings in the head while it is free to turn. This enables the spring pressure to be conveniently measured so that all the brushes may seat with the desired spring force.

By reason of the several turns of the spring around the hub of the arm a considerable turning of the head 20 corresponds to a comparatively small change in the spring pressure. Accordingly three screws with three openings might be sufficient for giving as fine an adjustment as ordinarily desired. However, to enable a finer adjustment additional threaded screw holes in the casing are provided and such additional holes are shown at 19 in Figs. 1 and 3.

Our brush holders are adapted for the very convenient securing of the electric connections. For this purpose we have shown two rigid arcual bus-bars 50 and 51 lying in the space within the dish-shaped frame 13 and connected with the main leads 52 and 53, which, as shown, are flexible members passing through openings in the frame head 13. The bus-bars are connected with the brushes by flexible connections. In the embodiment shown the two bus-bars have each three flexible terminal members to connect with the six sets of brushes shown. The terminal members of the bar 50 are designated 54 and those of the bar 51 are designated 55. Each of these terminal members is shown in Figs. 2 and 4 as passing through one of the openings 57 in the disk head 20 and as secured to the stud 22 by a flattened end 56 which lies between the clamping nuts 27 and 28.

With such connections as just described the removal of the nut 28 allows the disconnection of the flexible terminal member, and

then the brush holder can be freely removed, the brush arms and brushes passing readily through the openings 15 in the frame member.

It is customary to employ pig-tails directly connecting brushes with the brush holder (to make a better electric connection) though such pig tails are omitted for clearness in Figs. 1 to 5 inclusive. In Figs. 6 and 8 we have shown two pig tails 62 and 63 connected at one end to the brushes 31, by the clamping screws 36, and at the other end connected by screws 65 to ears 64 on one of the busbars 60 or 61 corresponding to the bars 50 and 51. Where the construction just described is employed, there need be no outside terminals. The passages 57 through the heads provide for the ready insertion of a screw driver to loosen the screws 65, connecting the pig tails to the busbars, and, when these pig tails are thus disconnected, the brush holder with the pig tails is readily removed by the removal of the head 20. In this construction it is desirable to insulatingly protect the outer end of the shaft 22 and its clamping nuts, and this may be readily effected by an insulating dome-shaped cap 70 screwing onto the washer 26.

A simpler manner of carrying the stud 22 is by securing it directly to the head 20 by bakelite. This is illustrated in Fig. 7, where the head 20 has a cup-like cavity 75 facing the interior of the machine and having an annular groove 76, and the stud 22 is provided with an annular groove 77. 78 indicates bakelite filling the space around the stud and within the cavity and occupying the grooves and thus effectively securing the stud to the head.

It will be seen that in any of the forms shown, the electric connections may be readily disconnected, and the brushes, together with their carrying arms and stud, readily removed through the adjacent opening by simply disconnecting the head 20.

Having thus described our invention, what we claim is:

1. The combination, with a dynamo having an opening through its frame adjacent to the exterior of the commutator or collector, of a brush holder having a swinging arm in the interior of the dynamo frame and having supporting means removably secured to the frame adjacent said opening and independent of the support for the armature shaft, said opening being large enough for the removal of the brush holder through it.

2. The combination with a dynamo frame having an opening, of a brush holder in the interior of the frame adjacent to said opening, said holder comprising a stud, means carrying it and extending through the opening and removably secured to the exterior of the frame, an arm pivotally

mounted on the stud and adapted to carry a brush, and a spring acting on said arm, the opening being large enough for the removal of the brush and arm assembled.

5 3. The combination with a dynamo frame having an opening, of a head removably secured to the exterior of the frame and extending over the opening, a stud projecting from said head into the space within the 10 frame, an arm rotatively mounted on said stud, a brush carried by said arm, and a spring acting on the arm, said opening being large enough to allow the removal through it of the brush, arm, spring and the 15 portion of the stud on which the arm is journaled.

4. The combination with a dynamo having a plurality of openings through its frame adjacent to the exterior of the commutator or collector, a plurality of heads adapted to be secured to the frame across said openings, a stud carried by each head, an arm pivoted on each stud, and a spring acting on each arm, each opening being 25 large enough to permit the removal through it of the arm when mounted on the stud.

5. The combination with a dynamo having an end frame plate with openings through it, individual disk members independent of the armature shaft and secured to the outside of the frame plate across said openings, each disk member having a stud, an arm pivoted on the stud, and a brush carried by the arm, the arm and brush being adapted for removal through the opening in the frame.

6. The combination with a dynamo having an end frame plate with openings through it, individual disk members independent of the armature shaft and secured to the frame plate across said openings, each disk member having a stud, an arm pivoted on the stud, a brush carried by the arm, and a spring acting on the arm.

45 7. In a dynamo, the combination of a frame member having an opening through it adjacent to the exterior of the commutator or collector, a member adapted to be secured to the exterior of the frame adjacent to said 50 opening and independent of the support for the armature shaft, means carried by said member and extending through the opening and carrying a brush holder, and means adapted to secure the last mentioned member in various angular positions to the dynamo frame.

8. The combination of a dynamo having an end frame member with a plurality of openings through it arranged in an annular 60 row registering with the space about the exterior of the commutator or collector and independent of the armature and concentric of its axis, a plurality of disk heads, one for each opening, means adapted to secure 65 each head to the outside of the frame in a

plurality of positions, and a brush-holding arm carried by each head.

9. The combination of a dynamo having an end frame member with a plurality of openings through it arranged in an annular 70 row registering with the space about the exterior of the commutator or collector, a plurality of disk heads, one for each opening, screws adapted to secure each head to the frame in a plurality of positions, a stud 75 carried by each head, a brush-holding arm on each stud, and a spring acting on each arm.

10. In a dynamo, the combination of a frame member having an opening through 80 it adjacent to the exterior of the commutator or collector, a disk-like member adapted to extend across the opening, screws arranged equi-distantly about the disk-like member and adapted to secure it in various 85 angular positions to the outside of the dynamo frame, and a device for carrying a brush secured to said disk-like member.

11. In a dynamo, the combination of an end frame member having an opening 90 through it adjacent to the exterior of its commutator or collector, a disk-like member adapted to extend across the opening, screws arranged equi-distantly about the disk-like 95 member and adapted to secure it in various angular positions to the dynamo frame, a stud carried by the disk-like member and extending into the opening, and an arm pivotally mounted on the stud and adapted to carry a brush.

100 12. The combination with a dynamo, of a brush holder therefor, comprising a head adapted to be secured to the dynamo frame, a stud projecting from said head, an arm having a hub mounted on the stud, a helical spring coiled about the hub of the arm and secured at one end of the arm and the other end to the stud, and a plate carrying said stud, there being an opening through the frame through which the brush holder may be removed, said opening being bridged by 110 said plate.

105 13. In a dynamo, the combination of an end frame member having an opening through it adjacent to the exterior of the commutator or collector, a brush holder having a member independent of the support for the armature shaft and adapted to be secured to the exterior of the dynamo frame adjacent to the opening, a stud carried by the last mentioned member and extending through the opening, an arm having a hub mounted on the stud, a helical spring coiled about the hub of the arm and secured at one end to the arm and the other end to the stud, said opening being of sufficient 115 size to enable the removal of the stud, arm and spring intact.

120 14. In a brush holder, the combination with a supporting member, of a stud car- 125 130

ried thereby, an arm rotatably mounted on the stud and having a hub at one side of the arm, a helical spring surrounding the hub and secured at one end of arm, a collar surrounding the stud, and means whereby the other end of the spring anchors the collar to the stud.

15. In a dynamo, the combination with an end frame member having an opening 10 through it, of a disk-like head, means for securing it in various angular positions across said opening, an axial stud carried by said head, an arm on said stud having a hub, a helical spring coiled around said 15 hub and anchored to the arm and at the other to the stud and a brush carried by the arm.

16. In a dynamo, the combination of an end frame member having openings through 20 it arranged in an annular row, registering with the space about the exterior of the commutator or collector, a series of individual disk-like members, one for each opening, equidistant screws adapted to secure 25 said disk-like members in various positions across said opening, a stud carried by each disk-like opening extending parallel with the axis of the commutator or collector and insulatingly carried by the disk-

like member, an arm surrounding said stud, 30 a brush carried by the arm, a collar for positioning the arm, and a helical spring surrounding the stud anchored at one end of the arm and at the other end to both the collar and stud.

35. 17. The combination, with the stationary field frame of a dynamo, of a removable end member therefor having a plurality of openings through it adjacent to the exterior of the commutator or collector, a plurality 40 of heads adapted to be removably secured to said end member across said openings, a stud carried by each head, an arm pivoted on each stud, a brush carried by each arm, and electric connections for the respective 45 brushes.

18. The combination of a dynamo frame, a removable bell secured to the end of the frame, an annular series of removable heads secured to the bell, a brush holder carried 50 by each head and removable through openings in the bell, bus-bars housed within the bell, and flexible conductors in electric connection with the bus-bars and the brushes.

In testimony whereof, we hereunto affix 55 our signatures.

CHARLES E. F. AHLM.
HARRY Y. HALL.
